UNITED STATES PATENT OFFICE.

WILLIAM B. LUCAS, OF RIVER FOREST, ILLINOIS, ASSIGNOR TO LUCAS SIGNAL & CONTROL COMPANY, A CORPORATION OF ILLINOIS.

ELEVATOR SIGNALING SYSTEM.

1,124,632.

Specification of Letters Patent.

Patented Jan. 12, 1915.

Application filed February 25, 1910. Serial No. 545,832.

To all whom it may concern:

Be it known that I, WILLIAM B. LUCAS, a citizen of the United States, residing at River Forest, in the county of Cook and State of Illinois, have invented a certain new and useful Improvement in Elevator Signaling Systems, (Case 1,) of which the following is a full, clear, concise, and exact description, reference being had to the accompanying drawings, forming a part of this specification.

My invention relates to an elevator signaling system in which means are employed for signaling the operator of the elevator from various floors or levels, and for indicating at such different floors or levels the approach of the elevator.

My invention has for its object the simplification of mechanism required to accomplish the results set forth and, in the preferred embodiment, electrical circuits are employed which are adapted to actuate electromagnetic indicating mechanism at the different floors or levels with the use of a minimum amount of wiring. In carrying out my invention I may also employ electric lamps for indicating at the different floors or levels the approach of the elevator and, if desired, for indicating to the operator on the elevator a signal sent from one of the floors or levels.

My invention is susceptible of a variety of embodiments as, for example, signals may be associated with the different floors or levels in such a manner that each is adapted to be operated whenever the elevator approaches the corresponding floor or level; again, different signals may be associated with each floor or level and so arranged that one signal at each floor will operate whenever the elevator approaches in one direction, while the other signal at the same floor, having a different characteristic indication, will be operated whenever the elevator approaches the corresponding floor from the other direction; again, whether a common signal is used at each floor to indicate either direction of approach of the elevator, or whether two signals, having different characteristic indications are employed at each floor, mechanism may be employed which must first be operated by a person at such floor to cause the operation of the corresponding signals

when the elevator approaches such floor; again, the operation of the actuating means at each floor may also cause actuation of a signal in the elevator by means of which the elevator operator is advised that a passenger is waiting at a floor immediately in advance of the elevator; again, the mechanism employed for signaling the elevator operator may be used in connection with a continuously operated signaling device at the different floors or levels.

My invention further provides for automatically causing the actuation of the signals at the different floors at any desired distance in advance of the elevator, such mechanism being so actuated as to operate the signals at the different floors in advance of the elevator for either direction of its motion.

The several drawings illustrating my invention are as follows:

Figure 1 is a diagrammatic drawing of the circuit mechanism and electrical devices that may be employed to operate a system of lamp signals at the different floors or levels whenever the elevator approaches such floors from either direction. Fig. 2 shows, in a drawing similar to Fig. 1, an arrangement of electric circuits and electrically operated mechanism by means of which push buttons located at the different floors must first be operated before the signaling mechanism located at such floors is operated. In this figure there is also shown a signal on the elevator which signal is operated simultaneously with the actuation of the floor signals placed in operative condition by one of such push-buttons. Fig. 3 shows, in a view similar to Figs. 1 and 2, an arrangement of electric circuits, and mechanism adapted to be operated thereby so arranged that characteristic signals located at the different floors indicate the approach of the elevator from directions corresponding to such signals. Push-buttons are located at the different floors adapted by their operation to actuate a signal carried by the elevator to indicate to the operator that a signal is sent from a floor he is approaching. Fig. 4 shows, in diagrammatic view, a form of mechanical indicator that may be actuated at the different floors by means of the electrical apparatus. Fig. 5 is a detail view of the resistance-controlling mechanism em-

ployed to cause the operation of the electromagnetic mechanism at the different floors.

Similar numerals refer to similar parts 5 throughout the several views.

As shown in Fig. 1, the elevator 1 is supported by a cable 2 passing over sheaves 3 and 4 down the elevator well and around a sheave 5 at its lower end from which it 10 passes to any suitable hosting mechanism not shown. The sheave 5 carries a small pulley 6 around which a belt 7 is located, such belt encircling at its other end a comparatively large pulley 8 mounted upon the 15 shaft 9. The pulley 8 has rigidly secured to it a comparatively small pulley 10 which carries a belt 11 encircling at its other end a comparatively large pulley 12 carried by the spindle 13 of the rheostat 14. The spindle 20 13 has rigidly secured thereto a disk 15 which carries insulated contacts 16 and 17 disposed to be engaged by a relatively movable contact 18 carried by the contact making arm 19 which is loosely mounted upon 25 the spindle 13. The spindle 13 is thus in electrical contact with the arm 19 but insulated from the contacts 16 and 17. The arm 19, as it is rotated by the belt 11, engages the contacts 20 of the rheostat between 30 which the resistance 21 is connected.

The spindle 13 is connected to the terminal 22; the contacts 16 and 17 are connected to the terminals 23 and 24; and one end of the resistance 21 is connected to the terminal 25 of the rheostat.

Since the position of the arm 19 determines the operation of the signals at the different floors, it is necessary that there be no lost motion between the sheave 5 and 40 the spindle 13 and it is necessary, therefore, that the belts and pulleys employed be of a kind adapted to positively engage and drive the different parts, as, for example, sprocket wheels and chains.

At the several floors or levels the relays 26, 27, 28 and 29 are located one at each floor, the windings of these relays being included in series and connected by wires 30 and 31 with one terminal of the battery 32 and the terminal 25 of the rheostat 14 respectively. The other terminal of the battery 32 is connected through a switch 33 to the terminal 22 of the rheostat 14. The relays 26, 27, 28 and 29 are provided with 50 armatures 26^a, 27^a, 28^a and 29^a having back-contacts 26^b, 27^b, 28^b and 29^b respectively, and front contacts 26^c, 27^c, 28^c and 29^c respectively. The armature 26^a is connected by a wire 34 to the wire 30 and one terminal 60 of the battery 32. The front contact 26^c of the armature 26^a is connected by a wire 35 with the armature 27^a. The front contact 27^c of the relay 27 is connected by a wire 36 with the armature 28^a, and the front contact 28^c of the relay 28 is connected by a wire

37 with the armature 29^a, and this system of connection is followed for all of the different floors or levels regardless of their number. The back contact 26^b is connected by a wire 38 with the lamps 39 and 40, the other terminals of which are connected, by wires 41 and 42, with the terminals 23 and 24 of the rheostat 14. The back contact 27^b is connected by wire 43 with the lamps 44 and 45, the other terminals of which are connected to the wires 41 and 42 respectively. The back contact 28^b is connected by wire 46 with the lamps 47 and 48, the other terminals of which are connected respectively with the wires 41 and 42. The back contact 29^b is connected by wire 49 with the lamps 50 and 51, the other terminals of which are connected with the wires 41 and 42 respectively.

The relays 26, 27, 28 and 29 are so wound that they respond to different actuating currents, that is the relay 26 responds to a small current; the relay 27 to a larger current; the relay 28 to a still larger current; while the relay 29 requires a larger current to actuate it than does any of the other relays. This relation may be secured either by winding the relays with different sizes and amounts of wire, or by adjusting the armatures of the relays so that they have different degrees of sensitiveness, or both of these means may be jointly employed.

From the description above given, it will be observed that when the elevator is in its lowest position the arm 19 is in practically the position indicated in the drawing and that motion of the car to the first floor or starting point will serve to move the contact 16 into engagement with the contact 18 and also to move the arm 19 upon the first one 100 of the contacts 20, which, with the switch 33 in its closed position, closes a circuit through the actuating windings of the relays 26, 27, 28 and 29 as follows: battery 32, wire 30, windings of the relays 26, 27, 28 and 29 in series, wire 31, terminal 25, all of the resistance 21, arm 19, terminal 22, back to the battery 32. This condition preferably does not cause actuation of the relay 26 owing to the resistance 21 being too high, as a result of which the lamp 39 remains lighted, the current taking the following course: battery 32, wire 34, armature 26^a, contact 26^b, wire 38, lamp 39, wire 41, terminal 23, contact 16, contact 18, terminal 22 back to 115 battery 32. In other words, the lamp 39, by being illuminated indicates that the elevator is moving upward and that it has just approached the first floor. Further motion upward of the elevator moves the arm 19 around to the right, thus cutting out a portion of the resistance 21. The current increase resulting is sufficient to operate the relay 26, as a result of which the lamp 39 is 120 extinguished by the break between the arm- 130

ture 26^a and the contact 26^b and the lamp 44 is lighted through the following circuit: battery 32, wire 34, armature 26^a, contact 26^c, wire 35, armature 27^a, contact 27^b, wire 43, lamp 44, wire 41, terminal 23, contact 16, contact 18, terminal 22 back to battery 32. The lighting of the lamp 44 indicates that the elevator is moving upward and approaching the second floor. When the elevator 10 has reached the second floor the lamp 44 is preferably still lighted, which means that the resistance 21 has not been sufficiently reduced to cause the actuation of the relay 27. Further motion of the elevator 15 upward moves the arm 19 farther around to the right and the increase of current resulting from this further cutting off of the resistance 21 energizes the relay 27 which extinguishes the lamp 44 by separating the 20 armature 27^a from the contact 27^b and at the same time the lamp 47 is lighted by the following circuit: battery 32, wire 34, armature 26^a, contact 26^c, wire 35, armature 27^a, contact 27^c, wire 36, armature 28^a, contact 25 28^b, wire 46, lamp 47, wire 41, terminal 23, contact 16, contact 18, terminal 22 back to battery 32. The lighting of the lamp 47 indicates that the elevator 1 is moving upward and approaching the third floor. 30 When the elevator reaches the third floor, the lamp 47 is preferably still lighted and upon passing this floor the resistance 21 is cut out of circuit to a sufficient extent to cause the actuation of the relay 28 which, 35 by separating the armature 28^a from contact 28^b extinguishes the lamp 47 and lights the lamp 50 through the following circuit: battery 32, wire 34, armature 26^a, contact 26^c, wire 35, armature 27^a, contact 27^c, wire 36, 40 armature 28^a; contact 28^c, wire 37, armature 29^a, contact 29^b, wire 49, lamp 50, wire 41, terminal 23, contact 16, contact 18, terminal 22 back to battery 32. The lighting of the lamp 50 is an indication that the 45 elevator is moving upward and approaching the fourth floor.

It will be understood that apparatus similar to that described in connection with each of the first four floors is located at each of 50 the succeeding floors and that the operation of this apparatus is similar in all respects to the operation just described.

When the elevator 1 has reached the upper end of its travel and begins to move 55 downward, the disk 15 moves relatively to the arm 19 so as to break connection between the contacts 16 and 18 and close connection between the contacts 17 and 18. The resistance 21 included in circuit at this 60 time is of such amount as to cause the actuation of all of the relay windings serially included in the conductors 30 and 31, as a result of which all of the relay armatures are in their attracted position. As the car 65 moves downward and approaches the suc-

cessive floors the relays are deenergized and the lamps at the corresponding floors are lighted indicating that the elevator is moving downward and approaching such floors. As the car approaches the fourth floor, a 70 sufficient amount of the resistance 21 is brought into circuit by the arm 19 to deenergize the relay 29, thus lighting the lamp 51 through the following circuit: battery 32, wire 34, armature 26^a, contact 26^c, 75 wire 35, armature 27^a, contact 27^b, wire 36, armature 28^a, contact 28^c, wire 37, armature 29^a, contact 29^b, wire 49, lamp 51, wire 42, terminal 24, contact 17, contact 18, terminal 22, back to battery 32. As the car 80 moves further downward, more of the resistance 21 is included in circuit and the relay 28 is deenergized which, by the separation of the armature 28^a from the contact 28^c, extinguishes the lamp 51 and 85 lights the lamp 48 through the following circuit: battery 32, wire 34, armature 26^a, contact 26^c, wire 35, armature 27^a, contact 27^b, wire 36, armature 28^a, contact 28^b, wire 46, lamp 48, wire 42, terminal 24, contact 90 17, contact 18, terminal 22, back to battery 32. The lighting of the lamp 48 indicates that the elevator is moving downward and approaching the third floor. As the elevator passes the third floor a sufficient 95 amount of resistance 21 is included in the circuit to cause the deenergization of the relay 27 which, by the separation of the armature 27^a and the contact 27^c, extinguishes the lamp 48 and lights the lamp 45 100 through the following circuit: battery 32, wire 34, armature 26^a, contact 26^c, wire 35, armature 27^a, contact 27^b, wire 43, lamp 45, wire 42, terminal 24, contact 17, contact 18, terminal 22, back to battery 32. The lighting of the lamp 45 indicates that the elevator is moving downward and approaching the second floor. As the elevator passes the second floor, a sufficient amount of 105 resistance 21 is included in the circuit to cause the deenergization of relay 26 as a result of which, by the separation of the armature 26^a and the contact 26^c, the lamp 45 is extinguished and the lamp 40 is lighted through the following circuit: battery 32, 110 wire 34, armature 26^a, contact 26^b, wire 38, lamp 40, wire 42, terminal 24, contact 17, contact 18, terminal 22 back to battery 32. The lighting of the lamp 40 is an indication that the elevator is moving downward 115 and approaching the first floor.

From the foregoing description it will appear that the lamps 39, 44, 47 and 50 serve as signals at the several floors indicating the approach in the upward direction of the elevator 1, while the lamps 40, 45, 48 and 51 indicate an approach of the elevator in the downward direction. By using a color for the lamps 39, 44, 47 and 50, different from that employed for the 120

125 130

lamps 40, 45, 48 and 51, each signal at each floor serves to indicate definitely the direction of approach of the elevator to such floor.

5 In the system shown in Fig. 2, the circuit connections of the windings of the relays 26, 27, 28 and 29 are identical with the connections of the corresponding windings in Fig. 1, as a result of which they do not call
 10 for a detailed explanation. Furthermore the rheostat 14 is of similar construction to the rheostat shown in Fig. 1 and is similarly operated, its operation serving in the manner described in connection with Fig. 1
 15 to operate the several relays 26, 27, 28 and 29 as the elevator approaches the corresponding floors in either direction. As shown in this figure, push buttons 52, 53, 54 and 55 are located at the floors correspond-
 20 ing with the lamps 39, 44, 47 and 50 respectively. The push button 52 is adapted by its operation to energize the operating magnet of the relay 56, by a circuit as fol-
 25 lows: battery 57, wire 58, push button 52, winding 56, wire 61 back to battery 57. The push buttons 53, 54 and 55 are adapted by
 30 similar circuits closed from the battery 57 to energize the operating magnets of the re-
 35 lays 62, 65 and 68 respectively. The relay 56 by its operation attracts the armature 69 thus closing a circuit from the back contact 26^b of the relay 26 to the wire 38 as fol-
 40 lows: back contact 26^b, armature 69, contact 73, releasing winding 56^a, wire 38. In its
 45 attracted position the armature 69 is en-
 gaged by a catch 77 pivoted at 77^a which serves by the action of gravity to engage the upper end of the armature and retain it in its attracted position thus maintaining
 50 closed the connection above referred to be-
 tween the back contact 26^b and the wire 38 until the winding 56^a is energized. The catch 77 has rigidly connected thereto and extending downward from the pivot 77^a, an
 55 armature 77^b adapted to be attracted by the left hand end of the core upon which the winding 56^a is mounted. The armature 69 is provided at its lower end with a button 69^a by means of which it may be moved me-
 60 chanically into engagement with the catch 77, thus establishing connection between the back contact 26^b and the wire 38 without the energization of the winding 56 if desired. The relays 62, 65 and 68 are provided with
 65 armatures 70, 71 and 72 adapted to be en-
 gaged by the pivoted catches 78, 79 and 80 to which are secured the armatures 78^b, 79^b and 80^b arranged and conformed in a man-
 70 ner similar to the corresponding parts
 75 shown and described in connection with the relay 56. The relays 62, 65 and 68 are adapted by their operation to make connec-
 80 tion between the back contacts 27^b, 28^b and 29^b of the relays 27, 28 and 29 and the wires
 85 43, 46 and 49 respectively.

It is to be noticed that the wires 38, 43, 46 and 49 are normally discontinuous and that, therefore, the signal lamps disposed at the several floors are normally inoperative. In order that these lamps at any floor may 70 be placed in operative condition, either the corresponding one of the push buttons 52, 53, 54 and 55 must be actuated, or the corre-
 75 sponding one of the armatures 69, 70, 71 and 72 must be mechanically actuated to en-
 80 gage the corresponding catch to complete the circuit between the back contact of the associated one of the relays 26, 27, 28 and 29 and the wire connected with the lamps to be lighted. Assuming that connection 80 has been established between the back contact 28^b and the wire 46, the lamps 47 and 48 are in condition to be lighted by the opera-
 85 tion of the relays 27 and 28 as already de-
 scribed in connection with the system shown 85 in Fig. 1 in that the elevator 1 carries a pilot signal 81 which is connected in cir-
 90 cuit between the battery 32 and the arma-
 95 ture 26^a by means of the conductors 34 and 82 which are flexible at that portion ex-
 100 tends from the terminal block in the ele-
 105 vator well to the elevator.

From the above it will be understood that when the car is moving upward and reaches the floor below the signals 47 and 48, the 95 rheostat 14 will have been operated suffi-
 110 ciently to reduce the resistance so that the relay 27 is energized, as a result of which current will flow from the battery 32 through the lamp 47 as above described, 100 at the same time flowing through the lamp 81, thus indicating both to the operator on the elevator and to the person on the floor corresponding to the lamp 47 that the elevator is approaching. The current 105 thus flowing through the wire 46 and the winding 65^a attracts the armature 79^b, thus disengaging the catch 79 from the armature 71 which, however, is still retained in its 110 attracted position, as a result of the mag-
 115 netic action of the core upon which the winding 65^a is mounted. This condition continues until the elevator reaches the floor corresponding to the lamp 47 or slightly thereafter depending upon the adjustment 115 at which time by the reduction of the re-
 120 sistance 21 included in circuit the relay 28 is energized and thus the circuit through the wire 46 is broken. The armatures 69, 70, 71 and 72 are constructed so as to be com-
 125 paratively quick in their action and that this may be the case the retractile springs indicated are provided. The armatures 77^b, 78^b, 79^b and 80^b are, on the other hand, comparatively sluggish in their action, as 125 a result of which when the relay 28 is en-
 130 ergized, the armature 71 is pulled back from its attracted position before the catch 79 drops to its engaging position and thus the apparatus is restored to its normal relation. 130

- If, instead of moving upward, the car is moving downward toward the floor corresponding to the button 54 after the armature 71 has been engaged by the catch 79, the relay 28 will be deenergized when the elevator reaches the floor above the button 54 and the lamps 48 and 81 will be lighted, thus indicating that the car is approaching the floor corresponding to the button 54 from an upward direction and at the same time indicating to the elevator operator that he is to stop at the next floor. This condition continues until the elevator reaches the floor corresponding to the button 54 at which time the relay 27 is deenergized thus breaking the circuit through the wire 46 and therefore through the lamps 48 and 81 which circuit interruption releases the armature 71 as above described.
- In the modified system shown in Fig. 3, the relay arrangement used at each floor is similar to that shown and described in connection with Fig. 2, the only difference being in the circuit connections employed.
- In this system the floor signals 39, 44, 47, 50 and 40, 45, 48 and 51 are connected and operated as shown in Fig. 1. The elevator 1 is provided with a pilot signal 81, as shown in Fig. 2 adapted to be lighted only upon the setting of a button at one of the floors in advance of the elevator for either direction of its motion, the lighting of the pilot signal being controlled by the relay mechanism referred to above.
- As shown in Fig. 3, the pilot lamp 81 is connected between the conductors 84 and 85, the conductor 85 serving as a feed wire also for the elevator chandelier 86 from which the conductor 87 extends back to the battery 32. The conductor 84 is connected to the pivotal points of all of the armatures 69, 70, 71 and 72, any one of which, therefore, when in its attracted position serves to close the return path from the pilot lamp 81 to the corresponding wire 38, 43, 46 or 49 and thus through the corresponding back contacts 26^b, 27^b, 28^b and 29^b to the battery 32.
- From the above description it will be observed that with the system shown in Fig. 3, the pilot signal on the elevator is lighted as the elevator approaches a floor only if the signaling button at such floor has been operated but that the signals lighted at that floor are flashed as the elevator approaches from either direction whether the signaling button has been actuated or not, and further that the operation of the relay mechanism is identical with that shown and described in Fig. 2, the result of which operation being, in the system shown in Fig. 3, merely to control the pilot lamp on the elevator 1.
- As indicated diagrammatically in Fig. 4, the lamp signals associated with the various floors may be dispensed with and in their stead mechanical signals may be used operated directly by the magnets 26, 27, 28 and 29. As shown in this figure, each of the armatures 26^a and 27^a, is provided at its upper end with a roller 26ⁱ, 27ⁱ adapted to engage a cam surface formed on the lower edges of the levers 88 and 89 pivoted respectively at 90 and 91. The left hand ends of the levers 88 and 89 have secured thereto shutters 92 and 93 adapted to present characteristic indications to the openings 94 and 95 formed in the front board of the apparatus, such openings being so disposed as to be readily visible by the persons waiting at the different floors or levels.
- From the description already given of the magnets 26, 27, 28 and 29, it will be seen that the armatures 26^a, 27^a, 28^a and 29^a may be attracted one after the other as the elevator approaches the corresponding floors and that, by properly proportioning the magneto-motive forces of the different magnets and the retracting springs associated with their armatures, this operation may be effected before the cars reach the floors as desired. This mechanism thus may be made to afford an indication of the approach of the elevator in either direction.
- In Fig. 5, I have shown a means for securing any desired advance of the operation of the floor signals for either direction of motion of the elevator. As shown in this figure, the spindle 13 of the rheostat has rigidly secured thereto an arm 96 from the upper end of which a pin 97 projects into engagement with a slot 98 formed in the lower end of a lever 99, pivoted at 100 to an arm 101 loosely mounted upon the spindle 13. The upper end of the lever 99 has projecting therefrom a pin 102 adapted to engage a slot 103 formed in the lower end of a contact blade 104 pivoted at 105 to the arm 101. The upper end of the contact blade 104 is adapted to engage the several contacts 20 of the rheostat 14 as the spindle 13 is rotated. The arm 101 has rigidly secured thereto insulating blocks 105 and 106 through which the screws 107 and 108 are threaded, such screws adapted to be adjusted in such blocks by means of the milled heads indicated and to be clamped in any desired position by the check nuts 109 and 110. The screws 107 and 108 are connected by means of flexible connectors with the terminals 24 and 23 of the rheostat 14.
- From the construction just described, it will be understood that reversal of the motion of the spindle 13 serves not only to interrupt the circuit between the spindle 13 and one of the terminals 23 and 24 and to establish connection between such spindle and the other of such terminals, but that such reversal of motion also serves to rapidly move the contact blade 104 in advance of the direction of motion of the spindle 13.

until the arm 96 strikes one of the screws 107 and 108 depending upon the direction of motion of the spindle 13. The amount of motion of the spindle 13 relative to the arm 101 which is permitted by the adjustment of the screws 107 and 108 determines the amount of advance of the contact blade 104 ahead of the spindle 13 and thus determines whether the floor signals are operated one floor, two floors, or more, in advance of the approaching elevator.

It will be understood that while the windings of the relays 26, 27, 28 and 29 are shown as in series arrangement, they may be connected, if desired, in parallel and that by properly proportioning the windings they may be caused to successively operate by changing the potential impressed upon their terminals by means of the rheostat 14.

20 While I have shown my invention in the particular embodiments herein described, I do not, however, limit myself to these arrangements, but claim any equivalents that may suggest themselves to those skilled in 25 the art.

What I claim is:

1. In an elevator signaling system, the combination of a signal at each level, magnets successively responsive to different current strengths, circuit connections extending to the signals and controlled by the magnets for causing the operation of a given signal when the elevator approaches the level of such signal, and means operated by 30 motion of the elevator for changing the amount of resistance in circuit with such magnets to thereby control their successive operation.

2. In an elevator signaling system, the 40 combination of signals at different levels, magnets successively responsive to different current strengths, circuit connections extending to the signals and controlled by the magnets for causing the operation of such signals, a resistance and a source of current in circuit with such magnets, and means operated by motion of the elevator for changing the amount of resistance in circuit to control the successive operation of such 45 magnets and signals when the elevator approaches the level of such signals.

3. In an elevator signaling system, the combination of normally inoperative signals at different levels, push buttons associated 55 with such signals, magnets responsive to different current strengths, circuit connections for the signals and the push buttons and controlled by the magnets by which they control such signals when the corresponding push buttons are operated, a source 60 of current in circuit with such magnets, and means operated by motion of the elevator for changing the current flow in said circuit to successively control such magnets

when the elevator approaches the level of 65 the corresponding signals.

4. In an elevator signaling system, the combination of normally inoperative signals at different levels, magnets responsive to different current strength for controlling 70 said signals, push buttons associated with said signals for placing said signals under the control of said magnets, a source of current in circuit with said magnets and means operated by the motion of the elevator for 75 changing the current flow in said circuit to control the magnets when the elevator approaches the level of the corresponding signals.

5. In an elevator signaling system, the 80 combination of normally inoperative signals at different levels, push buttons associated with such signals, magnets responsive to different current strengths, circuit connections for the signals and the push buttons and controlled by the magnets by which they control such signals when the corresponding push buttons are operated, a resistance and a source of current in circuit with such magnets, and means operated by 85 motion of the elevator for successively controlling such magnets by changing the resistance included in circuit with them when the elevator approaches the level of the corresponding signals. 95

6. In an elevator signaling system, the combination of signals at different levels, a magnet associated with each signal for controlling the operation of the same, a single circuit extending to such magnets said magnets being responsive to different current strengths, a resistance and a source of current in such circuit, and means controlled by motion of the elevator for changing the amount of resistance in such circuit to thereby control such magnets when the elevator approaches the level of the corresponding signals. 100

7. In an elevator signaling system, the combination of a plurality of signals at different levels, a magnet associated with each signal, a push button associated with each signal, said signals being jointly controlled by said push buttons and said magnets, said magnets being connected in a single circuit 110 and being responsive to changes in current flow in the circuit and means controlled by motion of the elevator for changing the current flow in said circuit. 115

8. In an elevator signaling system, the 120 combination of a plurality of normally inoperative signals at different levels, a circuit for said signals, a magnet associated with each signal for controlling the circuit of the associated signal, push buttons associated with said signals, said push buttons operable to place said signals under the control of the magnets, said magnets being re- 125

sponsive to different current values, a common circuit for said magnets and means controlled by movement of the elevator for changing the value of the current in said circuit.

9. In an elevator signaling system, the combination of electric lamp signals at different floors, relays responsive to different current strengths associated with such signals, an electric lamp signal on the elevator, push buttons associated with such relays, a resistance and source of current in circuit with such relays, circuit connections extending from said relays to said signals and push buttons to control the operation of said signals, and means operated by motion of the elevator for changing the resistance included in circuit to successively control the operation of such relays when the elevator approaches the level of the corresponding signals, the operation of a given push button serving to light the electric lamp signal at the corresponding floor when the corresponding relay is operated, such relay also adapted to close and open the circuit through the electric lamp on the elevator as the elevator approaches and recedes from the level of the operated push button. 70

10. In an elevator signaling system, the combination of electric lamp signals at different floors, relays, circuit connections extending from said relays to said signals and push buttons to control the operation of said signals, associated with such signals, an electric lamp signal on the elevator, push buttons associated with such relays, a resistance and source of current in circuit with such relays, and means operated by motion of the elevator for changing the resistance included in circuit to successively control such relays when the elevator approaches the level of the corresponding signals, such relays also adapted by their operation to control the circuit through the electric lamp on the elevator. 75

11. In an elevator signaling system, the combination of electric lamp signals at different floors, relays, circuit connections extending from said relays to said signals and push buttons to control the operation of said signals, associated with such signals, an electric lamp signal on the elevator, push buttons associated with such relays, a resistance and source of current in circuit with such relays, and means operated by motion of the elevator for changing the resistance included in circuit to successively control such relays when the elevator approaches the level of the corresponding signals, each of such relays also adapted by its operation to close and open the circuit through the electric lamp on the elevator when the elevator approaches and recedes from the level of an operated push button. 80

12. In an elevator signaling system, the combination of electric lamp signals at different floors, relays responsive to different current strengths associated with such signals, an electric lamp signal on the elevator, push buttons associated with such relays, a resistance and source of current in circuit with such relays, circuit connections extending from said relays to said signals and push buttons to control the operation of said signals, and means operated by motion of the elevator for changing the resistance included in circuit to successively control such relays when the elevator approaches the level of the corresponding signals, the operation of a given push button serving to light the electric lamp signal at such floor when the corresponding relay is operated, such relay also adapted to close the circuit through the electric lamp on the elevator as the elevator approaches such floor. 85

13. In an elevator signaling system, the combination of electric lamp signals at different floors, relays responsive to different current strengths adapted by their operation to control the electric lamp circuit at a given floor when the elevator approaches the level of such electric lamp, circuit connections extending from such relays to said lamps to control the operation of the same, and means operated by motion of the elevator for changing the amount of resistance in circuit with such relays to thereby control their successive operation. 90

14. In an elevator signaling system, the combination of electric lamps at different floors, a relay associated with each lamp for controlling the circuit of the same, said relays being responsive to different current strengths, a single circuit extending to such relays, a resistance and source of current in such circuit, circuit connections extending from said relays to said lamps for controlling the operation of the same, and a controller operated by motion of the elevator for changing the amount of resistance in such circuit to thereby control such relays when the elevator approaches the level of the corresponding electric lamps. 95

15. In an elevator signaling system, the combination of normally inoperative electric lamps at different floors, push buttons associated with such lamps, relays responsive to different current strengths adapted to control such lamps when the corresponding push buttons are operated and when the elevator approaches the level of such lamps, a resistance and source of current in circuit with such relays, circuit connections extending from said relays to the lamps and push buttons to control the operation of said lamps, and means operated by motion of the elevator for successively controlling such relays. 100

16. In an elevator signaling system, the

- combination of normally inoperative electric lamps at different floors, push buttons associated with such lamps, relays responsive to different current strengths adapted to operate such lamps when the corresponding push buttons are operated and when the elevator approaches the level of such lamps, a resistance and source of current in circuit with such relays, circuit connections extending from said relays to said lamps and push buttons for controlling the operation of said lamps, and means operated by motion of the elevator for successively controlling such relays by changing the resistance included in circuit with the same. 15
17. In an elevator signaling system, the combination of signals at different levels, magnets responsive to different current strengths associated with and adapted to control the operation of such signals, a resistance and a source of current in circuit with such magnets, circuit connections extending from said magnets to the signals to control the operation of the same, and means operated by motion of the elevator for changing the amount of resistance in circuit to control the successive operation of such magnets and signals when the elevator approaches the level of such signals, said means serving to control the signals in advance of the elevator as desired. 25
18. In an elevator signaling system, the combination of normally inoperative signals at different levels, push buttons associated with such signals, magnets adapted to control such signals when the corresponding push buttons are operated and when the elevator approaches the level of such signals, a source of current in circuit with such magnets, circuit connections controlled by said magnet extending to the signals, and push buttons for controlling the operation of said signals, and means operated by motion of the elevator for successively controlling such magnets and thereby said signals, said means serving to control such signals in advance of the elevator as desired. 40
19. In an elevator signaling system, the combination of electric lamp signals at different floors, relays responsive to different current strengths associated with such signals, an electric lamp signal on the elevator, push buttons associated with such relays, a resistance and source of current in circuit with such relays, circuit connections extending from said relays to said signals and push buttons for controlling the operation of said signals, and means operated by motion of the elevator for changing the resistance included in circuit to successively control such relays when the elevator approaches the level of the corresponding signals, such relays adapted by their operation to control the corresponding floor signals and the elevator signal, said means serving to control the signals in advance of the elevator as desired. 55
20. In an elevator signaling system, the combination of electric lamp signals at different floors, relays responsive to different current strengths associated with such signals, an electric lamp signal on the elevator, push buttons associated with such relays, a resistance and source of current in circuit with such relays, circuit connections extending from said relays to said signals and push buttons for controlling the operation of said signals, and means operated by motion of the elevator for changing the resistance included in circuit to successively control such relays when the elevator approaches the level of the corresponding signals, the operation of a push button at any floor serving to light the electric lamp signal at such floor when the corresponding relay is operated and to light the electric lamp on the elevator as the elevator approaches such floor, said means serving to control the signals in advance of the elevator as desired. 70
21. In an elevator signaling system, the combination of electric lamps at different floors, a relay associated with each lamp for controlling the circuit of the same, a single circuit extending to such relays, a resistance and source of current in such circuit, and a controller operated by motion of the elevator for changing the amount of resistance in the circuit to thereby control such relays when the elevator approaches the level of the corresponding lamps, such controller serving to control the electric lamps in advance of the elevator as desired. 85
22. In an elevator signaling system, the combination of normally inoperative electric lamps at different floors, push buttons associated with such lamps, relays for controlling such lamps when the corresponding push buttons are operated and when the elevator approaches the level of such lamps, a source of current in circuit with such relays, and means operated by motion of the elevator for successively controlling such relays, such means controlling the electric lamps in advance of the elevator as desired. 105
23. In an elevator signaling system, the combination of two electric lamps at each floor adapted to give different indications, relays responsive to different current strengths associated with such lamps, push buttons associated with such relays, a resistance and source of current in circuit with such relays, circuit connections extending from said relays to said lamps and push buttons for controlling the operation of said lamps, and means operated by motion of the elevator for changing the resistance included in circuit to successively control such relays to light one of the corresponding lamps for upward motion of the elevator and to light the other of such lamps for 110
- 120
- 125
- 130

downward motion of the elevator when the elevator approaches the level of such lamps.

24. In an elevator signaling system, the combination of two electric lamps at each floor adapted to give different indications, relays responsive to different current strengths associated with such lamps, an electric lamp on the elevator, push buttons associated with such relays, a resistance and source of current in circuit with such relays, circuit connections extending from said relays to said lamps and push buttons for controlling the operation of said lamps, and means operated by motion of the elevator for changing the resistance included in circuit to successively control such relays, the operation of a push button at a given floor serving to light one of the corresponding lamps for upward motion of the elevator and to light the other of such lamps for downward motion of the elevator when the elevator approaches the level of such floor lamps, such means operating the lamps in advance of the elevator as desired. 70

25. In an elevator signaling system, the combination of two electric lamps at each floor, relays responsive to different current strengths adapted by their operation to control a lamp circuit at a given floor when the elevator approaches such floor, circuit connections extending from the relays to the lamps, and means operated by motion of the elevator for changing the amount of resistance in circuit with such relays to control their successive operation to light one of the corresponding lamps for upward motion of the elevator and to light the other of such lamps for downward motion of the elevator when the elevator approaches the level of such lamps. 80

26. In an elevator signaling system, the combination of normally inoperative electric lamps at different floors, push buttons associated with such lamps, relays for operating such lamps when the corresponding push buttons are operated, a resistance and a source of current in circuit with such relays, circuit connections extending from said relays to said lamps and push buttons for controlling the operation of said lamps, and means operated by motion of the elevator for successively controlling such relays by varying said resistance to light one of the corresponding lamps for upward motion of the elevator and to light the other of such lamps for downward motion of such elevator when the elevator approaches the level of such lamps. 90

27. In an elevator signaling system, the combination of two electric lamps at each floor adapted to give different indications, relays responsive to different current strengths associated with such lamps, an

electric lamp on the elevator, push buttons associated with such relays, a resistance and source of current in circuit with such relays, circuit connections extending from said relays to said lamps and push buttons for controlling the operation of said lamps, and means operated by motion of the elevator for changing the resistance included in the circuit to successively control such relays to control the circuit through the electric lamp on the elevator and to light one of the corresponding floor lamps for upward motion of the elevator and to light the other of such floor lamps for downward motion of the elevator when the elevator approaches the level of such floor lamps, such means operating the lamps in advance of the elevator as desired. 75

28. In an elevator signaling system, the combination of two electric lamps at each floor adapted to give different indications, relays responsive to different current strengths associated with such lamps, an electric lamp on the elevator, push buttons associated with such relays, a resistance and source of current in circuit with such relays, circuit connections extending from said relays to said lamps and push buttons for controlling the operation of said lamps, and means operated by motion of the elevator for changing the resistance included in circuit to successively control such relays, the operation of a push button at any floor serving to control one of the lamps at such floor for upward motion of the elevator and the other of such lamps for downward motion of the elevator and to control the lamp on the elevator for motion in either direction of the elevator when the elevator approaches the level of the floor lamps, said means serving to control the electric lamps in advance of the elevator as desired. 85

29. In an elevator signaling system, the combination of two electric lamps at each floor, relays responsive to different current strengths adapted by their operation to control a lamp circuit at a given floor when the elevator approaches such floor, circuit connections extending from the relays to the lamps, and means operated by motion of the elevator for changing the amount of resistance in circuit with such relays to control their successive operation to thereby control one of the lamps at said floor for upward motion of the elevator and to control the other of said lamps for downward motion of the elevator when the elevator approaches said floor, said means controlling the lamps in advance of the elevator as desired. 95

30. In an elevator signaling system, the combination of normally inoperative electric lamps at different floors, push buttons associated with such lamps, relays for controlling the circuits of the lamps when the corresponding push buttons are operated, a

source of current in circuit with such relays, circuit connections extending from said relays to said lamps, and push buttons for controlling the operation of said lamps, and 5 means operated by motion of the elevator for successively controlling such relays to thereby control one of the lamps at a given floor for upward motion of the elevator and to control the other of the lamps at said 10 floor for downward motion of the elevator when the elevator approaches said floor, said means serving to control the lamps in advance of the elevator as desired.

31. In a controller for use in an elevator 15 signaling system, the combination of a resistance, a plurality of contacts connected with different portions of the resistance, a switch arm adapted to successively engage the contacts, an operating shaft, and multiplying levers between the shaft and the switch arm for advancing the switch arm as desired ahead of the operating shaft by the rotation of the latter.

32. In a controller for use in an elevator 25 signaling system, the combination of a plurality of contacts adapted to be connected to different portions of a resistance, a switch arm for successively engaging the contacts, an operating shaft, multiplying levers between the shaft and the switch arm for advancing the switch arm as desired ahead of the operating shaft by the rotation of the latter, and means for regulating the amount 30 of such advance.

33. In a controller for use in an elevator 35 signaling system, the combination of a plurality of contacts adapted to be connected to different portions of a resistance, a switch arm for successively engaging such contacts, 40 an operating shaft, multiplying levers between the shaft and the switch arm for advancing the switch arm as desired ahead of the operating shaft by the rotation of the latter, and two auxiliary contacts associated 45 with the switch arm, such auxiliary contacts adapted to be closed one by motion of the levers in one direction and the other by motion of the levers in the other direction.

34. In an elevator signaling system, a 50 plurality of contacts, a movable member, a contact arm mounted on said movable member, said arm adapted to make electric connection with said contacts, in succession, and means for varying the angular relation 55 of the contact arm and the movable member when the direction of motion of the movable member is reversed.

35. In an elevator signaling system, a 60 plurality of contacts adapted to be connected to a resistance, a movable member having motion relative to said contacts, a wiper arm mounted on said movable member and coming into engagement with said contacts successively, said wiper arm having an independent motion to vary the angular relation 65

of the arm and the movable member when the direction of motion of the movable member is reversed.

36. In an elevator signaling system, the 70 combination of a signal at each level, magnets responsive to different current strengths adapted by their operation to control a given signal when the elevator approaches the corresponding level, circuit connections extending to the signals and 75 controlled by the magnets, and means operated by motion of the elevator for changing the amount of resistance in circuit with the magnets to thereby control their successive operation.

37. In an elevator signaling system, the 80 combination of signals at different levels, magnets responsive to different current strengths, circuit connections extending from said magnets to said signals for controlling the operation of the same, and means operated by motion of the elevator for changing the amount of resistance in circuit with the magnets to thereby control 85 their successive operation.

38. In an elevator signaling system, the 90 combination of signals at different levels, magnets responsive to different current strengths associated with the signals to control the operation of the same, a resistance 95 and a source of current in circuit with such magnets, circuit connections extending from said magnets to said signals to control the operation of the same and means operated by motion of the elevator for changing the 100 amount of resistance in circuit to control the successive operation of the magnets and signals.

39. In an elevator signaling system, the 105 combination of normally inoperative signals at different levels, push buttons associated with such signals, magnets responsive to different current strengths for controlling the signals when the corresponding push buttons are operated and when the elevator 110 approaches the level of such signals, a source of current in circuit with such magnets, circuit connections controlled by said magnets extending to the signals, and push buttons for controlling the operation of 115 said signals, and means operated by motion of the elevator for successively controlling such magnets.

40. In an elevator signaling system, the 120 combination of normally inoperative signals at different levels, push buttons associated with such signals, magnets responsive to different current strengths for controlling such signals when the corresponding push buttons are operated and when the elevator 125 approaches the level of such signals, a resistance and a source of current in circuit with such magnets, circuit connections controlled by said magnets extending to the signals, and push buttons for controlling the 130

operation of said signals, and means operated by motion of the elevator for successively controlling such magnets by changing the resistance included in circuit with them.

- 5 41. In an elevator signaling system, the combination of electric lamp signals at different floors, relays responsive to different current strengths associated with such signals, an electric lamp signal on the elevator, 70
 10 push buttons associated with such relays, a resistance and source of current in circuit with such relays, circuit connections extending from said relays to said signals and push buttons for controlling the operation 75
 15 of said signals and means operated by motion of the elevator for changing the resistance included in circuit to successively control such relays when the elevator approaches the level of the corresponding signals, 80
 20 such relays also adapted by their operation to control the circuit through the electric lamp on the elevator.

42. In an elevator signaling system, the combination of electric lamp signals at different floors, relays responsive to different current strengths associated with such signals, an electric lamp signal on the elevator, 90
 25 push buttons associated with such relays, a resistance and source of current in circuit with such relays, circuit connections extending from said relays to said signals and push buttons for controlling the operation 95
 30 of said signals and means operated by motion of the elevator for changing the resistance included in circuit to successively control such relays when the elevator approaches the level of the corresponding signals, 100
 35 such relays also adapted by their operation to close and open the circuit through the electric lamp on the elevator when the elevator approaches and recedes from the floor at which a push button has been operated.

43. In an elevator signaling system, the combination of electric lamp signals at different floors, relays responsive to different current strengths associated with such signals, an electric lamp signal on the elevator, 110
 45 push buttons associated with such relays, a resistance and source of current in circuit with such relays, circuit connections extending from said relays to said signals and push buttons for controlling the operation 115
 50 of said signals, and means operated by motion of the elevator for changing the resistance included in circuit to successively control such relays when the elevator approaches the level of the corresponding signals, the operation of a push button at a 120
 55 given floor serving to control the electric lamp signal at such floor when the corresponding relay is operated, such relay also serving by its operation to control the circuit through the electric lamp on the elevator as the elevator approaches said floor. 125
 60
 65

44. In an elevator signaling system, the combination of electric lamp signals at different floors, relays responsive to different current strengths associated with such signals, an electric lamp signal on the elevator, 70
 push buttons associated with such signals, a resistance and source of current in circuit with such relays, circuit connections extending from said relays to said signals and push buttons for controlling the operation 75
 of said signals, and means operated by motion of the elevator for changing the resistance included in circuit to successively control such relays when the elevator approaches the level of the corresponding signals, 80
 the operation of a push button at a given floor serving to control the signal at said floor when the corresponding relay is operated and when the elevator approaches the level of such floor and motion of the elevator away from said floor serving to interrupt the control of said signal, said relay also adapted to control the circuit through the electric lamp on the elevator as the elevator approaches said floor. 90

45. In an elevator signaling system, the combination of two electric lamps at each floor adapted to give different indications, relays responsive to different current strengths associated with such lamps, an electric lamp on the elevator, push buttons associated with such relays, a resistance and source of current in circuit with such relays, circuit connections extending from said relays to said lamps and push buttons for controlling the operation of said lamps, and means operated by motion of the elevator for changing the resistance included in circuit to successively control such relays when the elevator approaches the level of the corresponding signals, such relays also adapted by their operation to control the circuit through the electric lamp on the elevator, said means also operating through the relays controlled thereby to control one of the corresponding lamps for upward motion of the elevator and to control the other of said lamps for downward motion of the elevator. 105
 110

46. In an elevator signaling system, the combination of two electric lamps at each floor adapted to give different indications, relays responsive to different current strengths associated with such lamps, an electric lamp on the elevator, push buttons associated with such relays, a resistance and source of current in circuit with such relays, circuit connections extending from said relays to said lamps and push buttons for controlling the operation of said lamps, and means operated by motion of the elevator for changing the resistance included in circuit to successively control such relays when the elevator approaches the level of the corresponding signals, the operation 115
 120
 125
 130

of a push button at a given floor serving to control one of the electric lamps at said floor for upward motion of the elevator and the other of the lamps at said floor for downward motion of the elevator when the corresponding relay is operated, the operated relay also controlling the circuit through the electric lamp on the elevator as the elevator approaches said floor.

47. In an elevator signaling system, the combination of signals at different levels, a magnet associated with each signal for controlling the same, a single circuit extending to such magnets, and means controlled by motion of the elevator for successively operating such magnets over such circuit when the elevator approaches the level of the corresponding signals.

48. In an elevator signaling system, the combination of electromagnetic signal mechanisms at different levels, a single normally closed circuit extending to such mechanisms, and means controlled by motion of the elevator for successively operating such mechanisms over such circuit when the elevator approaches the level of the signal mechanisms.

49. In a controller for use in an elevator signaling system, the combination of a plurality of contacts adapted to be connected to different portions of a resistance, a switch arm for successively engaging such contacts, an operating shaft, and multiplying levers for advancing the switch arm as desired ahead of the operating shaft by the rotation of the latter.

50. In an elevator signaling system, the combination of signal display means at different levels, a current strength controller actuated by motion of the elevator, and circuit connections extending from said controller to said signal display means, the operation of said controller causing said signal display means to indicate the position of the elevator.

51. In an elevator signaling system, the combination of electromagnetic signal mechanisms at different levels, said mechanism being responsive to variations in current strength, a circuit connected with said signal mechanisms, and means controlled by motion of the elevator for changing the current strength in said circuit to actuate the signal mechanisms to indicate the level of the elevator.

52. In an elevator a signaling system, an "up" signal and a "down" signal at each floor, a common return for said "up" signals and a common return for said "down" signals, a series of electromagnetic relays, one for each floor, said relays having front contacts and back contacts, a common feed circuit for said signals connected through the armature, and front contact of each relay, connections from the back contact of

each relay to the "up" and "down" signals of the corresponding floor, and means to operate said magnets in succession, said means being provided with switching means for disconnecting one of said common returns in accordance with the direction of motion of the elevator.

53. In an elevator signaling system, "up" signals and "down" signals, a common return for said "up" signals and a common return for said "down" signals, said common returns being normally disconnected, a series of electromagnetic relays, one for each floor, said relays having front contacts and back contacts, a common feed circuit for said signals connected through the armature, and front contact of each relay, a car signal in series with said feed circuit, connections from the back contact of each relay to both the "up" and "down" signals of the corresponding floor, and means to operate said magnets in succession, said means being provided with switching means for connecting one of said common returns to the feed circuit in accordance with the motion of the elevator car.

54. In an elevator signaling system, an "up" signal and a "down" signal at each floor, a common return for said "up" signals, a common return for said "down" signals, a plurality of relays having magnets operating on different current strengths, said relays having front and back contacts, a feed circuit for said signals connected through the armature, and front contact of each relay, connection from the back contact of each relay to both of the corresponding floor signals, a common series circuit for said relay magnets, a rheostat in series with said circuit, said rheostat being operated in accordance with the motion of the car, a switch controlled by said rheostat for connecting one of the common returns with the signal feed circuit in accordance with the direction of motion of the elevator car.

55. In an elevator signal system, an "up" signal at each floor, a "down" signal at each floor, a common return for said "up" signals and a common return for said "down" signals, a relay associated with each set of floor signals, said relay having front and back armature contacts, said circuit for said signals connected through the armature, and front contact of each relay, a connection for each set of floor signals connected to the back contact of the corresponding relay, a locking relay in each of said connections and a push button to close the circuit of the locking relay, means to operate said relays in succession corresponding to the motion of the elevator car.

56. In an elevator signaling system, a plurality of floor signals, a magnet associated with each floor signal, said magnets being responsive to different current

strengths, a series circuit for said magnets including a source of current, a rheostat operated in proportion to the movement of the elevator car for varying the current 5 in the circuit in accordance with the position of the car, said rheostat being provided with means for changing the relation between the resistance and the position of the car when the direction of motion of the car is reversed.

57. In an elevator signaling system, a plurality of floor signals, a relay associated with each set of floor signals for controlling the same, said relays responsive to different 15 current strengths, a series circuit connecting

the relays, a source of current and a resistance, and means to vary said resistance in amounts corresponding to the successive floors, said means being moved in accordance with the movement of the elevator car 20 and being advanced independently upon a reversal of motion of the elevator car.

In witness whereof, I hereunto subscribe my name this 23rd day of February, A. D. 1910.

WILLIAM B. LUCAS.
